COVER FOR DOOR LOCKS

Edward N. Jacobi, Milwaukee, Wis., assignor to
Briggs & Stratton Corporation, Milwaukee,
Wis., a corporation of Delaware

Application January 30, 1950, Serial No. 141,271

8 Claims. (Cl. 70—455)

1

This invention relates to locks and refers more particularly to "cylinder" locks of the type designed for use on automobile doors and decks, and which have a cylinder or plug rotatable by a proper key to and from a door locking position.

Since the cylinders or plugs of such locks have their key receiving ends exposed to all sorts of weather, it is customary to provide them with a cover, generally termed a "dust cover," which closes not only the key opening in the lock plug but the entire mouth of the bore in which the plug is rotatably received.

It is desirable that such a cover be of the automatically closing type, designed to be opened by pushing the key against it to swing it edgewise away from its closed position and spring loaded so that when the key is withdrawn the cover is automatically returned to its closed position covering the cylinder mechanism. A dust cover of this type is shown in Patent No. 2,213,814, issued to Edward N. Jacobi September 3, 1940.

Obviously it is important that the cover mounting and closing mechanism be as simple, inexpensive and compact as possible; and it is therefore an object of this invention to provide an automatically closing dust cover for automobile door locks and the like which is secured to the body of the lock by means of the same spring which biases the cover to its closed position.

Another object of this invention resides in the provision of a dust cover of the character described which may be inexpensively manufactured as a single die casting and which has a pivot so formed thereon as to enable the cover to be assembled to and retained on the body of a lock by a single quick and easy operation.

With the above and other objects in view, which will appear as the description proceeds, this invention resides in the novel construction, combination and arrangement of parts substantially as hereinafter described and more particularly defined by the appended claims, it being understood that such changes may be made in the precise embodiment of the herein disclosed invention as come within the scope of the claims.

The accompanying drawings illustrate one complete example of the physical embodiment of the invention constructed according to the best mode so far devised for the practical application of the principles thereof, and in which:

Figure 1 is a front view of the dust cover of this invention mounted on a lock body and occupying its closed position thereon, a portion of the cover being cut away to show detail;

Figure 2 is a sectional view through the cover

2 pivot, taken along the plane of the line 2—2 in Figure 1;

Figure 3 is a rear view of the lock body and cover detached from an automobile door;

Figure 4 is a sectional view taken along the plane of the line 4—4 in Figure 1; and

Figure 5 is a perspective view of the dust cover of this invention and the lock body on which the same is mounted, the two being shown separated but in their relative positions for assembly.

Referring now to the accompanying drawings, in which like numerals designate like parts throughout the several views, the numeral 5 designates generally a lock body which is mounted, by way of illustration, on an automobile door 6. The specific lock structure shown in the drawings is intended for use on the left front or driver's door of an automobile, but it will be understood that the right hand door lock is identical in structure except for the necessary reversal of shapes.

The lock body comprises a substantially cylindrical casing 7 having an integral lateral extension 8 at its front, and is preferably formed as a die casting having a plated and polished escutcheon 9 covering the exposed front face of the extension 8. A key actuated lock cylinder or plug 10 is rotatably mounted in a bore 11 in the casing which extends forwardly through the extension 8 to open to the front of the lock body. Rotational motion of this lock cylinder is, of course, transmitted through a stem or shaft (not shown) or other connection to the door latch mechanism.

The lock body may be readily mounted on an automobile door with the lateral extension 8 flatwise overlying the outer side of the door and with the casing 7 preferably projecting rearwardly through a sleeve 6' on the door to the interior thereof. For the purpose of securing the lock mechanism in place on the door, the casing 7 has a shallow flat-bottomed slot 12 along one side thereof in which a set screw 13, threaded through the sleeve 6', is adapted to engage. The slot and set screw are so disposed that the latter is accessible through an aperture in the rear side edge 14 of the door structure (and thus inaccessible when the door is locked closed), and the slot in the casing is tapered to increase in depth toward the front of the lock body (i. e., is shallower in the

direction of extracting the lock from the face of the door) so that the set screw tends to engage the bottom of the slot in the side of the lock body more tightly if the lock is pulled forwardly by its key or is pried forwardly under its extension by an unauthorized person attempting to remove it.

The dust cover 15 of this invention flatwise overlies the front face of the extension 8 on the lock body, and in its closed position covers the bore 11 and the keyway 16 in the lock cylinder or plug to preclude entry of dirt and water into the same. The dust cover is also preferably a die casting having its front face trimmed with an escutcheon cap 17 of plated and polished sheet metal. In outline the dust cover conforms substantially to the shape of the extension 8 on the lock body but has a shallow notch 18 in its edge directly above the lock cylinder, in which the key is adapted to be guidingly received to permit the key to be used as a pusher whereby the cover may be pressed downwardly and thus edgewise swung to its open position (indicated by a broken line 15' in Figure 1). The notch also provides clearance for the key to enable it to be inserted into the keyway without necessitating excessive movement of the cover.

The inner face or underside 19 of the cover is slightly hollowed, so as to provide a marginal rim 20 which abuts the front face of the extension 8 on the lock body. This rim has a slight downward recess 21 at its lowest point which, in the closed position of the cover, coincides with a drain hole 22 in the extension 8, directly below the lock cylinder. Any moisture accumulating behind the cover will settle into this recess and then flow through the drain hole, to the rear of the extension 8 and thence down into the door structure, to be thus carried away from the keyway so that there will be no possibility of such water freezing in the lock mechanism.

The cover is mounted for edgewise swinging movement across the front face of the extension 8 on the lock body by means of a pair of post-like stem members 23 which extend rearwardly from the under-side of the cover and together define a bifurcated trunnion which is rotatably journaled in a second bore 24 in the lateral extension of the lock body, spaced from the bore 11 and parallel thereto. A conical torsion and compression spring 25 concentrically surrounds the stem members and serves to bias the cover toward its closed position and at the same time urge it rearwardly into firm engagement with the front of the lock body. For this purpose, the spring has a laterally inwardly extending end portion 26 at its apex which is received between the posts to torsionally bias the stem toward the closed position of the cover, and a laterally outwardly extending portion 27 at its other end which reacts against the lock body.

The rear of the lateral extension of the lock body is slightly hollowed to provide a wide shallow recess 32 which accommodates the spring and the rear extremity of the trunnion. The outwardly extending straight end portion of the spring lies in the junction of the bottom 33 of the recess and the marginal rim 34 thereof and reacts torsionally against the rim of the recess to bias the cover to its normally closed position, while the expansive force of the spring, exerted against the bottom of the recess and a flange-like lug 35 on the rear of each of the posts, urges the cover rearwardly into firm engagement with the front of the lock body.

The cross section of each of the posts or stem members is substantially a segment of a circle, the apexes of the segments being spaced from one another by a distance at least equal to the diameter of the spring wire, to enable the inner end portion of the spring to be inserted between the posts by forward translating movement. The

flat faces 37 and 38 on each of the two posts are so disposed with respect to the corresponding flat faces on the other post as to face in opposite directions and lie in parallel, spaced apart planes. The straight inwardly extending end portion 26 of the spring is interposed between the posts and extends transverse to the trunnion axis, lying lengthwise along the flat faces 37 of the posts, which thus provide the effect of opposite jaws which do not align with one another, being laterally displaced along the inturned length of the spring wire. The flat faces 37 of the posts thus receive the torsional force of the conical spring, whereby the cover is at all times biased to its closed position.

The spring is compressed forwardly, as well as helically, and its rearward biasing force is taken by the lateral lugs 35 on the rear of the posts, each extending from one post toward the opposite post and substantially perpendicular to the flat face 37 against which the inwardly turned end portion of the spring reacts. The two lugs thus cooperate to receive the rearward thrust of the spring by which the cover is urged into firm engagement with the front of the lateral extension on the lock body. The free side edge of each lug is spaced from the opposite post face 38 a sufficient distance to define a slot into which the inner end portion 26 of the spring is adapted to be inserted by forward movement in the direction of the trunnion axis. As the outer end portion 27 of the spring is rotated about the trunnion axis to bring it into position against the rim 34 at the rear of the lateral extension of the lock body, and the inner end portion 26 is simultaneously pressed forwardly, the inner end hooks into place ahead of the lugs, assuming the position shown in Figure 3.

To define the open and closed positions of the cover, and particularly to retain the cover in its predetermined closed position into which it is biased by the spring, a stud 40 on the cover extending from its underside parallel to the trunnion and spaced therefrom, rides in an arcuate slot 41 in the lateral extension on the front of the lock body.

Because the rear face of the lock body extension is hollowed or recessed in the neighborhood of the bore 24 to accommodate the spring, and the wall of the extension is therefore relatively thin, an annular rim or shoulder 42 extends forwardly of the front face of the lock body and surrounds the trunnion bore 24 to provide adequate bearing surface for the trunnion.

Both the lock body and the dust cover of this invention lend themselves particularly well to die casting, since each is designed in a manner to simplify coring.

To facilitate die casting the cover, both faces 37 and 38 of each post diverge forwardly (i. e., the posts decrease in cross section toward the cover, as best seen in Figure 2) so that the slot or space between the posts may be cored from the front side of the cover through the thickness of the cover and to the rear of the stem to thus also define the lugs at the rear of the stem. This accounts for the aperture 43 in the face of the cover through which the core portion of one die mold member is withdrawn from between the slots, the taper of the posts providing draft to facilitate such withdrawal. This aperture, of course, is closed by the polished sheet metal cap 17 which fits over the front face of the cover. Thus in die casting the cover of this invention the slot between the

posts and the spring abutment lugs may be molded without the need for separate core members.

The lock body is similarly adapted to be die cast without complicated coring procedure, the taper of the set screw slot 12 along the side of the casing providing draft to facilitate withdrawal of a core portion of the mold member which forms the front face of the body, which core portion projects rearwardly through the lateral extension on the body in the same manner as the core portion which provides the slot between the posts on the cover casting. The arcuate bean slot 41 in the lateral extension of the lock body is therefore somewhat irregular in shape, as at 45, to provide for this rearwardly projecting core portion, but this irregularity is concealed, at the front face of the body, by the polished sheet metal escutcheon 9.

From the foregoing description, taken together with the accompanying drawings, it will be readily apparent that this invention provides an unusually simple and inexpensive mounting for a dust cover for an automobile lock or the like, by means of which the cover may be secured in place by a single spring which serves to bias the cover toward its closed position and at all times urges the cover rearwardly into firm engagement with the lock body.

What I claim as my invention is:

1. In a lock of the character described: a body having a bore opening to the front face thereof and having a lateral extension provided with a bore parallel to the first named bore; a lock cylinder rotatable in the first named bore; a cover for the mouth of said first named bore; a bifurcated pivot post on the underside of the cover projecting rearwardly through the second named bore to the rear of said extension to mount said cover for edgewise swinging motion to and from a closed position covering the mouth of said first named bore; a coiled torsion and compression spring at the rear of said extension surrounding the rear portion of said post and having one of its end portions extending laterally inwardly between the bifurcations of the pivot post and its other end portion engaging a portion on the body and reacting against the same to torsionally bias the pivot post in a direction which swings the cover toward closed position; a lug on at least one of the bifurcations of the pivot post, extending toward the other and against which said inwardly extending end portion of the spring reacts so that the expansive force of the spring urges the cover rearwardly toward the lock body; and cooperating stop means on said cover and on the body for defining the closed position of the cover.

2. The lock structure set forth in claim 1, further characterized by the fact that said lug extends only partway from said one bifurcation of the pivot post toward the other bifurcation, so that the free edge of said lug and said other bifurcation define a slot into which said inwardly extending end portion of the spring is adapted to be inserted during assembly of the lock, to enable it to be hooked ahead of said lug.

3. In a lock of the character described: a lock body having a bore opening to its front face to receive the cylinder of the lock; a lateral extension on the front of said lock body having a hole therethrough parallel to the bore in the lock body; a cover for the face of said lock body; a post-like stem extending rearwardly from said cover and rotatably received in said hole to mount the cover for swinging motion to and from a posi-

tion over the mouth of the bore, said stem being slotted from its rear end towards the cover to provide opposed segments; a lug extending laterally from the rear of each segment, partway toward the other segment; a coiled torsion and compression spring surrounding the stem; means connecting one end of the spring to the lateral extension of the lock body so as to react torsionally and axially against the rear of said extension; and the other end portion of the spring extending laterally inwardly between the stem segments ahead of the lugs thereon so as to torsionally bias the stem and cover against swinging away from a position at which the cover closes the mouth of the bore in the body, and to exert a rearward axial force on the lugs on the stem segments to urge the cover rearwardly toward the face of the lock body.

4. As an article of manufacture: a relatively flat cover; means defining a trunnion integral with the cover and extending rearwardly from the underside of the cover, perpendicular thereto, bifurcations on the rear of the trunnion, spaced apart substantially diametrically opposite abutments on said bifurcations, said abutments being spaced at opposite sides of and facing a plane containing the trunnion axis, and a lug on each bifurcation rearwardly adjacent to its abutment and extending across said plane to provide a surface facing the underside of the cover and spaced therefrom.

5. As an article of manufacture: a relatively flat cover; trunnion means integral with the cover and extending rearwardly from the underside of the cover, perpendicular thereto, said trunnion means comprising a pair of spaced apart post-like stem members having substantially radial side faces which intersect along lines spaced from the axis of the trunnion at opposite sides of said axis, a pair of said faces, one on each of said stem members, being spaced at opposite sides of a plane containing the trunnion axis and being substantially parallel to said plane, and lugs on the stem members projecting laterally from said pair of faces to define surfaces facing the underside of the cover and spaced therefrom.

6. In a lock of the type having a lock body with a forwardly opening bore therein to rotatably receive a key operable cylinder, a lateral extension of the front of the body, and a cover adapted to swing edgewise across the front of the body to and from a closed position covering the mouth of said bore, means for mounting the cover on said body and for yieldingly resisting opening motion of the cover, comprising: stem means on the cover extending rearwardly from the underside of the cover and defining a trunnion rotatable in a bore in said extension parallel to said first named bore, said stem means being bifurcated; a coiled compression and torsion spring surrounding said trunnion at the rear of said lateral extension and having one of its end portions engaged with the lock body and its other end portion extending laterally inwardly between said bifurcations and engaged with the same to torsionally bias the cover toward closed position; and a lug on the rear of each of said bifurcations overlying said inwardly extending end portion of the spring to receive the expansive force thereof so that the spring at all times urges the trunnion rearwardly to bias the cover into firm engagement with the lock body.

7. In a lock of the type having a lock body with a forwardly opening bore therein to rotatably receive a key operable cylinder, a lateral

extension of the front of the body, and a cover adapted to swing edgewise across the front of the body to and from a closed position covering the mouth of said bore, means for mounting the cover on said body and for yieldingly resisting opening motion of the cover, comprising; stem means on the cover extending rearwardly therefrom and defining a trunnion journaled in a bore in said extension parallel to said first named bore, said stem means being bifurcated to define a rearwardly opening slot; a coiled compression and torsion spring surrounding said trunnion at the rear of said lateral extension and having one of its end portions engaged with the lock body and its other end portion extending laterally inwardly into said slot and between said bifurcations; and a lug on the rear of at least one of said bifurcations under which said inwardly extending portion of the spring hooks and against which it exerts rearward bias to urge the cover into firm engagement with the front of the body.

8. In a lock of the character described: a lock body having a bore opening to its front face to receive the cylinder of the lock; a cover for the mouth of said bore; means mounting the cover on the body for swinging motion to and from a position flatwise engaging the front face of the body and closing the mouth of the bore therein, said means comprising a trunnion rotatably journaled

in the body, said trunnion having one of its ends joined to the cover and having bifurcations at its opposite end providing opposed segments; a lug extending laterally from each segment and providing an abutment facing the first designated end of the trunnion; a coiled torsion and compression spring surrounding said trunnion, said spring having one end reacting against the lock body and its opposite end extending laterally inwardly between the trunnion segments and seating against said abutments thereon so as to torsionally bias the cover against swinging motion away from its position closing the mouth of the bore in the body, and to exert a yielding axial force on the trunnion in the direction of its bifurcated end.

EDWARD N. JACOBI.
